ATTORNEY.

UNITED STATES PATENT OFFICE.

FRIEDRICH CARL STEPHAN, OF CRIMMITSCHAU, GERMANY.

MEASURING OF FABRICS.

No. 821,839.

Specification of Letters Patent.

Patented May 29, 1906.

Application filed May 21, 1904. Serial No. 209,117.

To all whom it may concern:

Be it known that I, FRIEDRICH CARL STEPHAN, manufacturer, a subject of the Emperor of Germany, residing at Crimmitschau, 5 in the Empire of Germany, have invented certain new and useful Improvements in and Relating to the Measuring of Fabrics, of which the following is a specification.

The invention relates to an improved method of carrying into practice the invention described in the specification of my prior United States Letters Patent, No. 713,524, dated November 11, 1902, relating to means for measuring and checking the length of 15 cloths and other fabrics, by means of which a measuring-strip is inserted between the two doubled layers of material and wound up together with the fabric in such a manner that the strip constantly alters its position between 20 the two layers of stuff during the winding, so that never more than one convolution of the strip comes above another, whereby the formation of a protuberance owing to accumulations of thicknesses of the paper strip 25 which would produce a mark in thin and delicate fabrics is obviated.

As described in the aforesaid specification, the measure-guide is actuated in this case also by the measuring-strip, which is being 30 wound up itself.

While, however, in accordance with the said prior specification the winding operation must be interrupted each time the measuring-guide *h* reaches the end of the beam *g*, this is 35 not necessary in accordance with the present invention, as the driving mechanism which forms the subject of this application moves the measure-guide not only outward, but backward, thereby making unnecessary the 40 reversal of the measure-guide by hand and obviating interruptions in the winding and measuring operations. In order to attain this end, a gear-wheel is fixed upon the spindle of the friction-roll carrying the measuring-strip, this wheel meshing with gearing. 45 The gearing drives a chain, which is carried over two chain-wheels. One of the links of this chain is articulated to one end of a rod, the other extremity of which is articulated to 50 the measuring-strip guide.

Figures 1 and 2 illustrate the device in plan and in side elevation, respectively. Fig. 55 3 is a detail view showing the gear-wheels and chain transmission for the measure-guide.

The box *b* is provided with a plate *a* for resting upon the winding-table and with a

pin *c* for the reception of the measuring-strip roll *d*. Upon unwinding, the measuring-strip *e* is carried round the friction-roll *f* and over the hollow beam *g*. This latter is provided 60 with the measure-guide *h*, which is formed with two oblique delivery-slots *i* and *k* for right and left hand winding.

Upon the spindle of the friction-roll *f* is mounted the pinion *l*, meshing with the gear-wheel *m*. On this latter is the pinion *n*, meshing with the gear-wheel *o*, upon the spindle of which the chain-wheel *p* is fixed. This latter is connected, by means of a chain *q*, with a second chain-wheel *r*, mounted in the beam *g*. 70 A rod *s* connects the chain *q* with the measure-guide *h*. The front edge of a cover *t* presses upon the measure-roll *d* in such a manner that the measure offers some resistance to unwinding, which must be greater 75 than the resistance to the rotation of the gearing. The cover also affords security against the falling out of the measuring-strip roll. By means of this mechanism the measuring-strip guide *h* experiences a constant uniform 80 reciprocating movement, so that the device acts quite automatically, and the winding operation need not be interrupted so long as the measuring-strip is not unwound.

What I claim, and desire to secure by Letters Patent of the United States, is—

1. In a machine for laying a measuring-strip between the folds or convolutions of a fabric, the combination of a friction-roller adapted to be rotated by the measuring-strip, a guide for laying the measuring-strip between the convolutions of the fabric, and means for effecting a reciprocation of the guide from the rotation of the friction-roller.

2. In a machine for laying a measuring-strip between the folds or convolutions of a fabric, the combination of a beam, a strip-laying guide mounted on said arm, a friction-roller mounted at one end of said beam and adapted to be rotated by the measuring-strip, gearing connected to said friction-roller for converting the motion of the friction-roller into reciprocating motion, and connections between said guide and said gearing for communicating said reciprocating motion to 105 the guide.

3. In a machine of the class described, the combination of a beam, a guide mounted on said beam and adapted to lay a ribbon at substantially right angles to said beam, of means 110 mounted on one end of said beam for reciprocating the guide, said means being actuated

by the material which is passed through said guide.

4. In a machine of the class described, a light portable beam, a reciprocating guide mounted on said beam, a plate for supporting and positioning said beam, and means mounted on one end of said beam for reciprocating said guide, said means being actuated by the measuring-strip.

5. In a machine for laying a measuring-strip upon the folds or the convolutions of a fabric, the combination with a beam and a receptacle containing a roll of measuring-tape mounted on said beam, of a friction-roller mounted in the receptacle and over which the tape is adapted to pass, a guide located at a short distance from the receptacle and means connected to said friction-roller and to said guide for reciprocating the guide from said friction-roller.

6. In a machine for laying a measuring-strip between the folds or convolutions of the fabric, the combination of a light portable beam, a reciprocating guide mounted on said beam, a box at one end of said beam for containing the measuring-strip, a friction-roller also mounted in said box and adapted to be driven by the measuring-strip, gearing attached to the friction-roller for reciprocating said guide, and a cover for said box adapted to retain the measuring-strip within the box and to apply friction thereto.

In testimony whereof I have hereunto set my hand, in presence of two subscribing witnesses, this 4th day of May, 1904.

FRIEDRICH CARL STEPHAN.
